UNITED STATES PATENT OFFICE.

FRANÇOIS RENÉ MARCEL, OF BROOKLYN, NEW YORK.

HAIR-WAVING DEVICE.

1,290,622.

Specification of Letters Patent. Patented Jan. 7, 1919.

Application filed May 3, 1916. Serial No. 95,019.

To all whom it may concern:

Be it known that I, FRANÇOIS RENÉ MARCEL, a citizen of the United States, and a resident of the borough of Brooklyn, city 5 and State of New York, have invented certain new and useful Improvements in Hair-Waving Devices, of which the following is a specification.

My invention relates to a device for im- 10 parting curls or waves to women's hair. The object of the invention is to provide a simple and efficient device for imparting the "Marcel" wave to the hair and without danger of injuring it. Another object is 15 to provide a device which women may use and manipulate readily for waving their own hair and without the skill usually possessed by expert hairdressers.

Heretofore it has been difficult for women 20 to wave their own hair to produce the desired effect because the devices made for the purpose have not been successful or because those which were capable of producing the desired effect were adapted for use only by 25 the professional hairdresser. With my present invention a woman may very conveniently wave her hair and without danger of overheating or burning it.

In the drawings forming part of this ap- 30 plication,

Figure 1 is a perspective view showing one part of the device attached or applied to the hair for waving,

Fig. 2 is a plan view of the device which 35 is attached to the hair and of the device inserted therein to apply the heat,

Fig. 3 is an end view of the device which attaches to the hair, the same being shown closed, as when secured in place, but with- 40 out the hair,

Fig. 4 is an enlarged sectional view, showing the same opened to receive the hair,

Fig. 5 is a sectional view, taken on the line 5-5 of Fig. 4,

Fig. 6 is a longitudinal sectional view of 45 the electrical device for applying the heat,

Fig. 7 is a similar view taken at right angle to Fig. 6.

Fig. 8 is a perspective view of the heat- 50 ing prongs detached from the handle,

Fig. 9 is an end view of the parts shown in Fig. 8,

Fig. 10 is a sectional view, taken on the line 10-10 of Fig. 6,

Fig. 11 is a sectional view taken on the 55 line 11-11 of Fig. 6 and

Fig. 12 is a perspective view of one of the terminal connecting members.

The invention consists primarily of a de- 60 vice to be applied to the head and about which the hair may be twisted, and of means for applying heat to the hair.

The device herein shown and about which the hair may be twisted is shown in Figs. 65 1 to 5. It consists of a base 1 composed of members 2 and 3 which are pivotally connected by a pin 4. The connection is preferably made by a joint which will permit the members 2 and 3 to pivot in more than one direction. For instance I have shown, a 70 ball 5, on the member 3, which turns in a socket member 6, the slot 7 permitting the pin 4 to swing in one direction, while the members 2, 3 may also pivot about the pin 75 as an axis. The members 2, 3 may swing in their own plane on the pin 4 and they may be tilted to lie in converging planes.

Each of the members 2, 3 has a projection or stud 8 surrounded by a groove 9 and a tube 10 fits over the projection 8 and it has 80 one end seated in the groove, and a similar tube fits over the stud 8 of the member 3 and extends into the adjacent groove 9. This form of connection prevents the hair from getting between the parts and becoming caught and broken. The members 2, 3 may be made of any suitable material but I prefer to press or cast them of some such material as composite, which will stand the 85 heat and which will not be too heavy. I 90 prefer, however, to make the tubes 10, 11 of metal, although I do not wish to be understood as limiting myself to these particular materials.

The tubes 10, 11, it is to be understood, 95 are fixed to and are movable with, respectively, the members 2 and 3 and they project outwardly therefrom.

The underside of the base is curved to 100 form a substantially spherical recess 12 so

as to partially conform to the shape of the head and provide a wide bearing contact for the base upon the head.

There is a clip member preferably made 5 of spring metal and consisting of an intermediate loop 13 adapted to lie between the tubes 10, 11 and of loops 14, 15 on opposite sides thereof which fit around the respective tubes when the latter are brought close 10 together.

In preparing the hair a number of devices 15 as above described may be used, so that they may be applied at various positions around or on the head, each acting on some portion 20 of the hair and when they have all been placed in position with locks of hair twisted around them heat may be applied to them successively and they may then remain until sufficient heat has been applied to the hair 25 to fix the waves.

In using this branch of my invention the base 1 is placed against the head with the tubes 10, 11 projecting substantially at right angles thereto. The base members are slightly 25 swung open on the pin 4 as is shown in Fig. 4, to form a space 16 to receive the hair and to space the tubes apart. Instead of depending upon this slight separation of the tubes and trying to guide the hair around 30 and between them, which would be unhandy if a woman were manipulating the device on her own hair, it is preferable to tilt the base members 2, 3 so that they lie in slightly converging planes. This is permitted by 35 the movement of the pin 4 in the slot 7. This temporarily causes the tubes to separate at their outer ends, or to diverge, so that there will be a wider space between them at their outer ends where it will be 40 very easy to pass the hair between the tubes. This makes it unnecessary to separate the base members substantially beyond what is actually necessary to receive the hair in the space 16.

45 With the device temporarily held in the position just described, *i. e.*, with the tubes diverging, a lock of hair is brought up through the space 16 and it is then passed around one of the tubes, for instance 11, and 50 passed between the tubes and then reversely around the tube 10 and again between the tubes. This operation is carried on until the whole lock of hair has been wound around the tubes in a series of figures eight.

55 It is to be understood that the hair may be otherwise twisted around the tubes but the above arrangement will produce what is known as the "Marcel" wave.

When substantially the whole length of 60 the lock of hair has been twisted about the tubes, it is drawn taut by pulling on the end thereof. This will draw the tubes toward each other as close as the hair between them will permit. The clip is then pressed over 65 the tubes beyond the hair, so that the loop

13 lies between the tubes and the loops 14, 15 partially surround and clamp the tubes. The clip is then moved along the tubes toward the head, to press the loops of hair together and prevent them from working 70 loose from the tubes. The tighter the hair is drawn upon the tubes and the more securely held there the better and more permanent the wave. The clip now holds the tubes close to each other, they being only 75 separated by the intermediate lock of twisted hair and it is no longer necessary to hold the device in position.

The device will now remain in the position shown in Fig. 1, held there by the hair 80 itself. The base 1 will lie against the head and the tubes 10, 11 will project outwardly substantially at right angles to the head. If heat is applied to the tubes there is no danger of their coming into contact with the 85 scalp and causing discomfort or even a burn; and, on the other hand, the device is retained in this position by the hair.

Heat may now be applied to this first device and then other devices like the first one 90 may be attached at other positions on the head, so that while the heat is acting at one place to set the wave another device may be arranged for heating, and so on, until, when the last device has been applied, the first 95 one will have sufficiently heated the hair to set the wave, and be ready for removal.

The heat is furnished preferably by means of heating members temporarily inserted in the tubes 10, 11.

In Fig. 2 I have shown a device consisting of a handle 17 and two parallel prongs or tines 18, 19. The prongs 18, 19 may be heated in the same manner that an ordinary curling iron is heated. The prongs, after 100 being heated, are inserted into the tubes 10, 11, one prong in each tube. The heat of the prongs is transferred by conduction or radiation, or both, to the tubes. If the prongs are heated to a comparatively high temperature then they need be inserted in the tubes for only a very brief period. As the prongs do not come into direct contact with the hair they may be very hot without danger of 105 scorching the hair. After sufficient heat has 110 been imparted to the tubes the heating device is removed and the heat stored by the tubes is gradually given off by them to the hair.

While such a heater will accomplish the 120 purpose, nevertheless it is quicker and easier to use an electrical heater, such as that shown in Figs. 6 to 12.

Herein the prongs 20, 21 consist of hollow tubes arranged in parallel spaced relation, 125 the tubes being fitted in one member 22 of the handle. The other member of the handle comprises a tubular shell 23 having a screw threaded connection 24 with the member 22. The member 22 has a segmental extension 130

25 on which there is a raised portion 26 provided with a screw hole 27. The raised portion has an aperture 28 in its rear end, and there is a clamping block 29 which is secured 5 upon the member 26 by a screw 30 which is threaded into the aperture 27. The members 22, 25, 26 and 29 are all made of insulating material and for this purpose they may be cast from composite or some such 10 material.

There is a heating unit comprising a rod 31 inserted into each tube 20, 21. These electrical heating units are not shown in detail because they may be made like units 15 now in common use in electric curling irons. The units are preferably connected in series and for that purpose a wire 32 connects one terminal of one unit with a terminal of the other unit. The other terminals 33, 34 of 20 these units are carried back and are detachably connected with the cable wires 35, 36 respectively. The cable wires 35, 36 each have a split block on the end for clamping the terminals 33, 34. The wires 35, 36 each 25 have secured thereto one half 37, of the split block and the other half 38, is secured to the part 37 by means of a screw 39. The members 37, 38 have curved recesses 40 provided with cross teeth 41. A terminal from 30 one of the units is inserted in the recesses 40 of the block members and then the screw 39 is tightened to clamp these members together. The terminal wire will be tightly gripped and the teeth 41 will prevent the 35 split block from separating from the terminal wire. This forms a simple and efficient connection between the cable wires 35, 36 and the terminal wires of the heating units and it permits the assembling and dis- 40 assembling of the parts readily and without injury to the wires.

The cable wires 35, 36 are tied in a knot at 42 to prevent any tension on the cable from disarranging the connections between 45 the cable wires and the wires 33, 34. The cable 43 extends through a bushing 44 at the end of the handle 23 and it is connected up in the usual way with a source of electricity.

50 In assembling the device the heating units are inserted in the tubes 20, 21, the curved shape of the member 25 allowing free access to the tubes from the rear. This is done while the handle 23 is removed. The cable 55 43 is then passed through the aperture 28 and through the bushing 44. The wires 35, 36 are then tied at 42 so that they will not be further drawn through the aperture 28. While the handle is still removed, the blocks 60 38, 37 are clamped upon the respective terminals 33, 34 and they are secured by tightening the screws 39. The block 29 is now placed in position and screwed down. The handle 23 is now moved into position to 65 start the threads 24 and it is screwed on

the member 22. In manipulating the heater there is no danger of breaking the connections within the handle. This is important because the terminal wires are not adapted to stand much strain.

70

On the other hand, it is very easy to remove the handle, separate the connections, and remove the heating units. The ends of the heating units and the terminal wires 33, 34 are surrounded by insulating material, 75 and the member 28 separates the wires 35, 36 so that there is no possibility of an accidental short circuit within the heater.

This heater is used in the same manner as the heater shown in Fig. 2. The tubes 80 20, 21 are inserted into the tubes 10, 11 of the waver and the current is then turned on. The heat generated in the units 31 and given off by the tubes 20, 21 is imparted to the tubes 10, 11 to affect the hair and set the 85 wave.

The device is simple, easy to manipulate and it is inexpensive to manufacture. With it, a woman may easily wave her own hair and secure excellent results.

90

Having described my invention, what I claim is:

1. In a device of the class described, the combination of a base adapted to engage the head and comprising members connected to swing apart, an elongated member secured to each of said base members and extending in the same general direction and about which the hair is adapted to be twisted for the purpose set forth.

95

2. In a device of the class described, the combination of a base adapted to engage the head and comprising members pivoted to swing apart, an elongated member secured to each of said base members at a point separated from the pivotal point, said elongated members extending in the same general direction and adapted to be moved toward and from each other with the swinging of said base members.

100

3. In a device of the class described, the combination of a base adapted to engage the head and comprising members pivoted to swing toward and from each other and to tilt in relation to each other, an elongated member secured to each of said base members at a point separated from the pivotal point, said elongated members extending in the same general direction and adapted to be moved toward and from each other and to be tilted to diverge in relation to each other, with the movement of said base members.

115

4. In a device of the class described, the combination of a base adapted to engage the head and comprising members pivoted to swing toward and from each other and to tilt in relation to each other, a tubular member secured to each base member at a point separated from the pivotal point, said tubu-

120

125

130

lar members extending in the same general direction and adapted to be moved toward and from each other and to be tilted to diverge in relation to each other, with the 5 movement of said base members, and detachable means simultaneously insertible into both tubular members for the purpose of applying heat thereto.

5. In a device of the class described, the 10 combination of a base comprising pivoted

members, an elongated member secured to each of said base members, said elongated members extending in the same general direction and adapted to move with said base members, and a clip for engaging and slid- 15 able along said elongated members.

Signed at the city, county and State of New York, this 26 day of April, 1916.

FRANÇOIS RENÉ MARCEL.
